UNITED STATES PATENT OFFICE.

WILLIAM J. STEVENS, OF NEW YORK, N. Y., ASSIGNOR OF ONE-HALF TO
DAVID A. HOPKINS, OF PARK RIDGE, NEW JERSEY.

BALANCE SLIDE-VALVE.

SPECIFICATION forming part of Letters Patent No. 356,173, dated January 18, 1887.

Application filed October 30, 1886. Serial No. 217,557. (No model.)

To all whom it may concern:

Be it known that I, WILLIAM JAY STEVENS, a citizen of the United States of America, and a resident of the city, county, and State of New 5 York, have invented a certain new and useful Improvement in Balance Slide-Valves, of which the following is a specification.

This invention relates to the combination, in balance-valves with two opposite vertical slide- 10 valve seats, constructed on the steam or pressure cylinder and provided with suitable inlet and outlet ports from said cylinder and opposite vertical slide-valves, and a connecting-yoke or cross-head from the valve-rod to operate both together, of a pressure stop-plate at the top and a pressure stop projection or stud through the exhaust-port between and from one valve to the opposite, to construct and balance the pressure in the chest upon 15 the valves against their seats.

In the drawings hereto annexed, Figure 1 represents a lateral vertical section of a steam or pressure chest through the exhaust-port of the cylinder, with the balance-valves constructed according to my invention. Fig. 2 25 is a longitudinal vertical section of the same. Fig. 3 is a horizontal section taken through the ports of the same. Fig. 4 is a detached top view of the valves and seats of the same.

30 A represents the steam-chest seat and portion of the steam or pressure cylinder on which the ports and chests are applied.

B is the side case, and C the cover of the chest.

35 D represents the steam or pressure supply pipe attached to the cover.

E represents the hollow upward longitudinal projection within the chest, having two opposite vertical longitudinal sides for valve- 40 seats F F', with opposite inlet and outlet ports, and which seats are suitably planed and finished for the opposite vertical slide-valves G to operate.

The central belt exhaust-passage, H, continues into the central hollow portion, H', of the projection E, and said hollow portion H' has the exhaust opening or ports I I from it to each opposite valve-seat F, and the alternate inlet-passages J J of the cylinder communicate, through similar hollow portions J' in said

projection E, with the inlet-ports K K in the seats F F'.

Each valve G is suitably fitted to slide upon its seat with steam-tight joints, and having the usual hollow or concave portion, G', toward the seat, to allow the communicating passage from the inlets alternately to the common exhaust-port. Toward the valve-rod L each valve has a forward-projecting flat nose, M, which has a lateral notch, N, on its bottom side. 55 The end of the valve-rod L within the chest has the lateral cross-head or yoke O projecting with its ends under the nose M, engaging with an upward-projecting tooth, P, into the notch N of the nose of each valve, so that by 60 means of said cross-head both valves are reciprocated together. Said valve-rod passes through a suitable stuffing-box on the chest. In each concave portion G' of the valves are provided opposite hubs Q Q, and a lateral 65 stud, R, is secured with a shank, f, in the hub Q of one of the valves, and passing through both exhaust-ports to come in contact with its loose end with the hub Q of the opposite valve, so as to counteract the pressure of the valves 70 upon their seats at their lower portion. To counteract the pressure upon the valves at their upper portion, I provide a flat plate, S, between the valves above the projection E. The opposite upper portions of the valves are 75 for said plate S planed to recede from the bearing-surface, to allow a shoulder, T, on each for resting said plate a little above the top of the projection E, to admit the steam between said plate and the projection E, and above said 80 longitudinal plate S is employed a lateral plate, U, for the purpose of locking the plate S longitudinally from sliding out of place. The top of each valve has an opposite lateral notch, V, in which the ends or tenons b of the plate U 85 engage, and the portion of said plate U between the valves is fitted and engages between two lateral ribs, W W, projecting on the top side of the plate S. By this means said plate S is held from dislocating.

95 By the above construction of the balance-valve great convenience is obtained to repair or adjust the proper bearing of the valves against their counteracting stops and to the valve-seats. Such repair or adjustment is 90 100

frequently required with cylinders and slide-valves of high-speeded engines on account of the rapid travel of the valves, and their consequent wear of the valves upon their seats, 5 causing a leakage at the bearing-surfaces of the valves. To have access to the valves in such case, the cover C is first removed, the plate U and the plate S are simply raised and removed from their seats, and thereupon the 10 valve in contact with the end of the stud R can be raised and removed from the chest. The bearing-surface of the hub Q in contact with the stud R of the removed valve is now slightly reduced, scraped, or filed, and the 15 bearing-edge of the plate S is likewise reduced or scraped. With very little reduction the worn-off bearing-surfaces of the valves become properly steam-tight again and the valve is replaced, the plates S and U are placed upon 20 their seats, and finally the cover C is secured, which all may be done in a very short time. By having the counteracting stop or stud R arranged through the exhaust-ports I the chest is allowed to be much shorter than a chest in 25 which the valves have stops beyond the ends of the base of the projection E.

What I claim as my invention, and desire to secure by Letters Patent, is—

1. In balance slide-valves, the construction and combination, with the vertical opposite 30 valves G and their seats F, of the counteracting top plate, S, and a stop or stud, R, provided substantially as and for the purpose herein set forth.

2. The combination, with the projection E, 35 its ports I and K, the valves G, and their seats F, of the counteracting-plate S and stud or stop R, through the exhaust-ports and said plate S, with its locking-plate U, and the valves G G, with their notched noses M, and the cross-head O, with the rod L, substantially as and for the purpose herein shown and described.

In testimony that I claim the foregoing as my invention I have signed my name, in presence of two witnesses, this 25th day of October, 45 1886.

WM. J. STEVENS.
